PORTABLE COLONIC IRRIGATOR

Filed Sept. 14, 1936

UNITED STATES PATENT OFFICE

2,133,626

PORTABLE COLONIC IRRIGATOR

Frederick A. Mayberry, Wichita, Kans.

Application September 14, 1936, Serial No. 100,701

3 Claims. (Cl. 128—227)

My invention relates to improvements in portable colonic irrigating equipment. The object of my invention is to provide a portable colonic irrigating device which may be collapsed and packed in a case for transportation purposes. A still further object is to provide a device of the kind mentioned, in which the case, or a part of the case, may be used as a suitable table top to support the patient during the treatment of the patient; or a portion of the case may be employed as a supporting element for the drainage and irrigating device. A still further object is to provide a device of the kind mentioned in which the halves of the case may be supported on adjustable legs for purposes above mentioned while the other half of the case provides a housing and compartments for the irrigating equipment and accessories for the device and articles incidental to the performance of colonic irrigating. These and other objects will be more fully explained as this description progresses.

Referring to the drawing; Fig. 1 is a perspective view of the case folded up and ready for transportation.

Fig. 2 is a plan view of the case in an open position showing the equipment as it is packed in the case.

Fig. 3 is a top view of the case in a closed position, the top case elements being removed for convenience of illustration.

Fig. 4 is a side view of the irrigating tube, deflector shield and drainage assembly.

Fig. 5 is a sectional view through the deflector shield showing the water supply line, valve, check valve and method of attaching the irrigating tube to the water supply system just mentioned.

Fig. 6 is a side view of my colonic irrigating device set up for use in combination with a bed which is to be used for the partial support of the patient.

Fig. 7 is a plan view of the equipment shown in Fig. 6.

Fig. 8 is a side view of my colonic irrigating device set up for use in connection with a water closet such as is commonly found in the average home.

Fig. 9 is a plan view of the equipment and combination shown in Fig. 8.

In the drawing, similar numerals of reference designate the same part throughout the several figures.

In the drawing is shown a rectangular shaped case consisting of two halves 10 and 11 which are hinged together, with hinges 12 and 13. The hinges 12 and 13 are provided with loose pins so

that the pins may be removed from the hinges and the two halves of the case may be detached from each other. The section 11 of the case is provided with any suitable handle 14 by which the case may be carried. At 15 and 16 are shown clamp lock elements which may be employed to hold the top sides of the case together.

In the inside corners of the case portion 10 are block like elements 17, 18, 19 and 20, each of which are provided with a hole 17x, 18x, 19x and 20x, which are adapted to receive leg elements, as will later be described. Each of these blocks are provided with a thumb screw 17y, 18y, 19y and 20y, which are adapted to be screwed against the leg for the purpose of securing the leg in the block.

At 21 and 22 are cross ribs extending from side to side of the section 10 which function as a support for the side of the section 10 as well as a means of tightly packing the contents of the case as will later be described.

In the side of the case element 10 is an opening outlined by the line 23 in which is fitted a closure element 24, which is provided with rigidly attached block elements 25 and 26, which are so positioned that the element 24 may be placed in the opening 23 and the blocks will engage the element 10 to position the element 24 in flush relationship to the element 10 within the hole 23. At 27 and 28 is shown a pair of wing locks that are pivotally attached to the element 10 and the ends thereof adapted to be turned to overlap the edges of the element 24 as a means of retaining the element 24 in the opening 23.

In the section 11 of the case is a section comprising three compartments 29, 30, and 31, which are covered by a hinged cover element 32. These compartments are designed to carry the legs for the support of the section 10, another section for carrying the irrigating tubes, rubber gloves and other articles of use, incidental to the equipment, while the third compartment may be employed for carrying smaller articles such as bottles of Vaseline, powder and the like.

At 33 is a cross element extending side to side of the section 11 and setting in a slanting position from top to bottom as shown in Fig. 3, the object of which will be later explained.

At 34 is another open top compartment, in which is carried a rubber pad 35 and a syringe bag 36 and associated rubber hose and other articles if desired.

At 37 is the drainage element having sloping walls that fit between the elements 33 and the compartment 30, said element 37 being provided

with a rigidly attached, outwardly projecting L shaped element 38, which passes through a slot in the wall of the compartment 30 and functions as a means of stabilizing the element 37, is provided with an integral plate 39 which functions as a support for the drainage element 37 and associated elements, as will later be explained. Around the opening of the drainage element 37 are holes 40, the object of which will later be explained. At 41 is a pair of foot rests hingedly mounted on the plate 39 at the points 42 and 43.

At 44 is shown a shield or deflector element which is made of spring sheet material and carries a fitting which comprises a check valve 45 and a manually operated valve 46, which is provided with a tubular element that is adapted to receive one end of a rubber hose 47. The check valve fitting is threaded on one end of a tubular element 48 and functions to rigidly clamp the element 44 between the check valve fitting 45 and the nut 49.

As shown in Fig. 3, the shield element 44 rests on top of the plate 39 and the outer ends of the element 44 are engaged by the rib elements 21 and 22 in the case element 10, which when the case elements 10 and 11 are in a closed position, will press the element 44 to a flattened position and the spring pressure thereof is exerted against the plate 39 and functions to hold the elements 37, 39 and 44 in a comparatively tight, fixed position within the case so that the case may be carried and the elements therein will not rattle.

The element 44 is provided with a plurality of downwardly projecting leg like elements 50 that are rigidly attached to the element 44 and are so bent that the leg like portions thereof are spaced away from the sides of the element 44 so that the element 44 may be sprung in a curved formation and fitted within the opening 31x which passes through the plate 39 and drainage element 37, and the legs 50 will enter the holes 40 and function as a support for the element 44.

Since this equipment is one that will be used mostly in homes, it is obvious that some of these homes will be equipped with modern water closets, while others will not be so equipped, therefore the equipment must be applicable to either condition.

In view of this fact, Figs. 6 and 7 illustrate the device as being used where there is no water closet and the device is used in combination with a bed which forms a part of the support for the patient.

In setting up the outfit as shown in Figs. 6 and 7, the case 10-11 is opened and the pins in the hinges 12 and 13 are removed so that the sections 10 and 11 of the case are detached from each other and the portion 11 of the case contains all of the equipment as previously described, while a table like element is formed out of the element 10 of the case by placing the legs 51 in position in the sockets 17x, 18x, 19x and 20x and the thumb screws 17y, 18y, 19y and 20y are tightened against the legs to secure them rigidly to the case element 10 which forms a table like element for the outfit, which is set adjacent a bed 53 as shown in Figs. 6 and 7.

In as much as beds vary in height, it is necessary that the table element must also conform to the height of the bed. This is accomplished by auxiliary leg elements 53 which are threaded into leg elements 51 and may be screwed up or down therein to obtain the necessary height of the table element. The table element having thus been constructed and adjusted, the closure

element 24 is removed from the element 10 by turning the wing nuts 28, whereupon the element 24 readily drops from the element 10, leaving an opening as indicated by the line 23 in the top of the table like element, whereupon the drainage element 37-39 is assembled on the table element by passing the portion 37 through the opening in the table top whereupon the portion 39 rests on the table top to support the drainage element 37-39 and its associated parts. The baffle plate is then sprung to a curved position, whereupon it may be entered into the opening 31x of the drainage element and the legs 50 will enter the holes 40 in the plate 39 to support the baffle plate 44 in a forwardly tilted position as shown in Figs. 4, 6 and 7.

This having been done, a rubber pad 35 is placed over the front portion of the plate 39 and the table top and overlaps the joint between the table top and the mattress 55 of the bed. A pad 56 may be formed of blankets or quilts and laid on the mattress to build up a thickness equal to the rubber pad 35 so that a uniform, soft, comfortable surface is provided upon which the patient may lie.

This having been done, one end of a rubber hose 47 is slipped on the nipple of the valve 46, the opposite end of the hose 47 being attached to a water bag 36 which may be supported at an elevated position by being hung on the wall or being supported by any other suitable method.

This having been done, a slop jar or other suitable vessel 57 is placed under the drainage element 37 to receive the drainage from said drainage element. Said vessel 57 being supported on any suitable element, such as a foot stool or other suitable articles that may be found in any home. The foot rests 41 are turned outwardly as shown in Fig. 7 and the bag 36 is filled with water or other suitable liquid and the device is then ready for use.

The patient is laid on the bed and table element with the buttock of the patient positioned adjacent or between the sides of the shield 44 with the feet resting on the foot rests 41, whereupon the attendant places the outer end 59 of the irrigating tube 60 in the rectum of the patient. The opposite end of the irrigating tube 60 being joined to the nipple 48 by a short length of rubber hose 61 which provides the irrigating tube with an adjustment, in or out, as may be necessary to fit the individual patient and also provides a flexibility of the tube 60 which will permit limited movements of the patient without discomfort.

The tube 60, being supported from the shield 44 as described, is held in such a manner that it will not be expelled from the rectum during expulsion operations of the patient.

The apparatus and patient having been prepared for treatment as described, the valve 46 is opened and water or liquid from the bag 36 flows by gravity into the colon of the patient. After a certain amount of liquid has entered the colon, the patient may expell the liquid and the discharge will fall by gravity into the chamber 57 or if the discharge should strike the shield 44, its tilted position will direct the discharge into the chamber 57.

Attention is called to the fact that the irrigating tube 60, being supported from the shield 44 prevented the expulsion of the tube from the rectum. In the patient's act of expelling the contents of the colon, it is quite likely there was pressure therein, which would force foreign material 76

backward into the irrigating tube 60, if possible. This however is prevented by the check valve 45 closing to prevent the passage of material backward through the irrigating tube 60 and hose 47, etc.

5 In homes where a water closet is present, the irrigating device is used in connection with a water closet. This set up is shown in Figs. 8 and 9 in which the drainage element 37 fits within 10 in the opening in the seat 62 of the toilet with the plate 39 resting on the seat 62 and the projection 38 being positioned under the seat and above the china portion 63 of the toilet. This arrangement secures a rigid and dependable assembly of 15 the drainage element to the closet.

A table like element is formed of the case element 10 as previously described and adjusted to the proper height, so that the table may be set before the water-closet in a position that the 20 plate 39 will meet or overlap the edge of the table element associated therewith. In this assembly, the closure plate 24 in the element 10 is not removed, so that a complete table like top is maintained.

25 The rubber pad 35 and auxiliary pad 56 as previously described are employed in this assembly, the same as shown in Figs. 6 and 7, but are not shown in Figs. 8 and 9 for convenience of illustration. In using this assembly, the patient is supported on the table like element 10 30 in the same position as previously described and as indicated by the dotted lines A. The process of irrigation is the same as previously described, except that the discharge or drainage is caught 35 in the water closet 63.

Such modifications may be employed as lie within the scope of the appended claims without departing from the spirit and intention of the appended claims. Now having fully described my invention, what I claim as new and desire to secure by Letters Patent is:

1. A portable colonic irrigating device, including a case for the housing of the irrigating device and equipment, part of said case being convertible into a table like element, the other part of said case having compartments for housing equipment incidental to the device.

2. In a portable colonic irrigating device as described in claim 1, said table like element having an opening in the top thereof to receive a drainage element, said drainage element having a plate adapted to rest on the top of said table like element as a support for said drainage element, a shield, said shield being detachably attached to said plate and drainage element, a 15 check valve and a manually operated valve, said valves being rigidly supported by said shield and adapted to pass liquid therethrough, nipples connected to said valves and an irrigating tube 20 flexibly connected to one of said nipples and projecting outwardly from the concave side of said shield, the other nipple being adapted to receive one end of a hose for the delivery of liquid through said valves and irrigating tube.

3. In a portable colonic irrigating device, a case 25 for the housing of said device, a drainage element and a table like element, formed from a part of said case, said drainage element having a detachable shield carried thereon and flexibly supporting an irrigating tube and means for supplying liquid through said tube, the combination of said drainage element adapted to be supported on a water closet in position for drainage therein and said table-like element adapted to be positioned before the water-closet so that the table 30 like element and drainage element form a support for a patient, substantially as shown and described.

FREDERICK A. MAYBERRY.
